UNITED STATES PATENT OFFICE

2,594,050

CLASP TYPE CLOSURE FOR ENVELOPES

George H. Matthiesen, Chicago, Ill.

Application November 12, 1947, Serial No. 785,293

1 Claim. (Cl. 229—78)

1

This invention relates to clasp type closures for envelopes and more particularly to improvements in the clasp type closures disclosed and claimed in my copending application Serial No. 752,309, filed June 4, 1947, now Patent No. 2,555,983. This application is a continuation in part of my copending application.

In the aforementioned application, the clasp type closure for envelopes includes a first blank, a second blank, a clasp carried by the second blank and extending through the first blank whereby the two blanks are secured together by the clasp, and adhesive coatings on the blanks for securing them to the envelope flap and the envelope body. In the use of the clasp type closure, the envelope is first stuffed and then the clasp type closure is adhesively secured to the flap and body of the envelope, thereby greatly facilitating the sealing of envelopes but yet permitting easy opening thereof. To facilitate opening and closing of the envelope, the first blank is preferably provided with a hole and, as illustrated in the aforementioned application, the clasp carried by the second blank extends through the hole. While such an arrangement is quite satisfactory, yet there is a tendency for the blanks to rotate with respect to each other about the clasp, thereby necessitating alignment of the blanks before application to the envelope.

An object of this invention is to provide an improved clasp type closure member for envelopes of the kind above specified wherein one of the blanks is eliminated to decrease costs, wherein a single adhesively coated blank is carried by the envelope closure flap by means of a clasp and adapted to be adhesively secured to the envelope body for closing the envelope, and wherein rotation of the blank with respect to the flap is effectively prevented, thereby obviating the necessity for aligning the blank with respect to the flap before closing the envelope.

In this respect the envelope has the usual body and a closure flap provided with a hole. The closure member includes a substantially rectangular blank having an adhesive coating on one side, and a metallic clasp having an enlarged head engaging the adhesive coated side of the blank and having a pair of spaced prongs extending through slits in the blank for nonrotatably carrying the blank. The prongs of the clasp also extend through slits in the closure flap closely adjacent the hole therein and are bent over against the outside of the closure flap for nonrotatably carrying the clasp and hence the blank with the exposed adhesive coated side of the blank posi-

tioned to contact the envelope body when the closure flap is closed. When the envelope is stuffed, it is closed by adhesively securing the blank to the envelope body, the blank being held in proper position for closure because it is non-rotatably carried by the closure flap. When the envelope is subsequently opened by manipulation of the clasp, the flap material between the hole and the closely adjacent slits is readily ruptured so that an enlarged hole is provided for facilitating further closing and opening of the envelope. Other objects and advantages will become apparent to those skilled in the art upon reference to the accompanying specification, claim, and drawing in which—

Figure 1 illustrates an envelope in closed position with one form of the clasp type closure applied thereto;

Figure 2 is a view similar to Fig. 1 but shows the envelope opened;

Figure 3 is a perspective view illustrating the clasp type closure utilized in Figs. 1 and 2;

Figure 4 is a sectional view taken substantially along the line 4—4 of Fig. 2;

Figure 5 is a sectional view taken substantially along the line 5—5 of Fig. 1;

Figure 6 is a sectional view similar to Fig. 5 but showing the envelope flap being opened.

Referring to Figs. 1 to 6 of the drawing, the envelope is designated at 10 and includes a body portion 11 and a closure flap 12. The flap 12 is provided with a hole 13 for receiving a clasp.

The clasp member associated with the envelope body and envelope flap includes a substantially rectangular blank 15 having an adhesive coating 16 on one side. A metallic clasp 17 having an enlarged head 18 and spaced prongs 19 is associated with the blank 15. The prongs 19, as illustrated in Fig. 3, extend through slits in the blank 15 as at 20 with the enlarged head 18 located on the side of the blank having the adhesive coating 16.

The prongs 19 of the clasp 17 are inserted through the envelope flap 12 closely adjacent the hole 13. The prongs 19 in this respect extend through slits 22 in the envelope flap, and these slits may be formed by the actual insertion of the prongs 19 through the envelope flap or they may be preformed in the envelope flap for receiving the prongs 19.

In the formation of the clasp type closure, the blank 15 is located on the extended envelope flap 12, as indicated in Fig. 2, and then the prongs 19 of the clasp 17 are inserted through the blank 15 and the envelope flap 12 closely adjacent the

hole 13. The prongs 19 are then bent over, as illustrated in Fig. 1. Thus, the blank 15 and clasp 17 are non-rotatably secured to the envelope flap 12, rotation being prevented between the respective elements by reason of the prongs 19 extending through the slits 20 at 22 in the blank 15 and envelope flap 12, respectively. This relationship is illustrated in the sectional view of Fig. 4. Preferably, the envelopes are sold with the clasp type closure secured thereto in the aforementioned fashion.

To stuff and close the envelope is a simple process. In so doing, the envelope is stuffed to any desired extent, then the envelope flap is closed and the blank 15 adhesively secured to the envelope body 11. The adhesive utilized may be of any convenient type such as glue, pressure sensitive adhesive, or the like. When the blank is adhesively secured to the envelope body, the envelope is sealed shut by the clasp, and the relationship between the parts in this condition is illustrated by Fig. 5.

In order to open the envelope after stuffing and sealing, all that is necessary is to raise the prongs 19 to release the envelope flap, whereby the same may be opened, and Fig. 6 illustrates the relationship between the parts during the envelope opening operation. During the opening operation, the envelope flap between the slits 22 and the hole 13 may be ruptured for the purpose of enlarging the hole 13 to facilitate subsequent opening and closing of the envelope.

Thus, there is provided an improved clasp type closure for envelopes which is simple and inexpensive to manufacture and which may be effectively utilized in an extremely simple manner for closing envelopes which have been stuffed to varying degrees. In fact, the stuffing and closing procedure utilizing this arrangement is greatly simplified and takes considerably less time than when conventional clasp type closures are utilized. The adhesive coated blank 15 is at all times maintained in the correct position with respect to the closure flap 12.

While for purposes of illustration, one form of this invention has been disclosed, other forms thereof may become apparent to those skilled in the art upon reference to this disclosure, and, therefore, this invention is to be limited only by the scope of the appended claim and prior art.

I claim as my invention:

An envelope having a body and a closure flap provided with a hole, a substantially rectangular blank having an adhesive coating on one side, and a metallic clasp having an enlarged head engaging the adhesive coated side of the blank and having a pair of spaced prongs extending through slits in the blank for nonrotatably carrying the blank, said prongs also extending through slits in the closure flap closely adjacent the hole therein and bent over against the outside of the closure flap for nonrotatably carrying the clasp and hence the blank with the exposed adhesive coated side of the blank positioned to contact the envelope body when the closure flap is closed.
